CLAIM

The ornamental design for pair of nail clipper handles, as shown and described.

DESCRIPTION

FIG. 1 is a front left top perspective view.

FIG. 2 is a rear left bottom perspective view.

FIG. 3 is a left side view, the right being a mirror image of the left.

FIG. 4 is a top view.

FIG. 5 is a bottom view.

FIG. 6 is a front left top perspective view in an open position.

FIG. 7 is a rear left bottom perspective view in the open position.

FIG. 8 is a left side view in the open position, the right being a mirror image of the left.

FIG. 9 is a top view in the open position.

FIG. 10 is a bottom view in the open position.

FIG. 11 is a front left top perspective view of the top pair of nail clipper handles removed from the set for clarity of disclosure; and,

FIG. 12 is a rear left bottom perspective view of the handle below the top pair of nail clipper handles removed from the set for clarity of disclosure.

In the drawings, the broken lines are included only for the purpose of illustrating environment and form no part of the claimed design.

In the drawings, boundary lines are shown as dotted and dashed lines. The claimed subject matter extends to the boundary but does not include the boundary.

1 Claim, 5 Drawing Sheets
